THREAD HANDLING MECHANISM FOR
SEWING MACHINES

George William Nelson, Cleveland, Ohio, assignor
to Lewis Invisible Stitch Machine Company, St.
Louis, Mo., a corporation of Maine

Original application December 10, 1942, Serial No.
468,515. Divided and this application October
29, 1945, Serial No. 625,207

10 Claims. (Cl. 112—254)

1

The invention herein disclosed relates to a sewing machine of the kind that effects a predetermined number of stitch-forming operations and automatically stops. More particularly, the invention relates to thread handling mechanism for such sewing machines. The present application constitutes a division of my copending application Serial No. 468,515, filed December 10, 1942, and which matured into Patent No. 2,511,367, June 13, 1950.

An object of the invention is to provide thread handling mechanism that is simple, durable and effective in operation. Another object of the invention is to provide thread handling mechanism in a machine of the kind mentioned that includes certain arrangements operative upon formation of a predetermined number of stitch-forming operations to effect a severance of the thread and a pull-off of thread for the start of the next stitching cycle. A further object of the invention is to provide actuating mechanism for the thread handling mechanism.

The foregoing and more particular objects of the invention together with certain advantages thereof are realized in the illustrative embodiment of the invention disclosed in the drawings and described in detail below.

The drawings include:

Fig. 1 which is an isometric view of a button sewing machine embodying the invention;

Fig. 2 which is a side elevation of the same, partly in section;

Fig. 3 which is a side elevation of the side opposite to that shown in Fig. 2 and sectioned in part;

Fig. 4 which is a rear end elevation of the same, partly in section;

Fig. 5 which is a fragmentary plan with a side cover open;

Fig. 6 which is a fragmentary top plan of the machine, partly in section;

Fig. 7 which is a bottom plan of the machine;

Fig. 8 which is a sectional plan taken on the line 8—8 of Fig. 2;

Fig. 9 which is a transverse section taken on the line 9—9 of Fig. 8;

Fig. 10 which is a front end elevation, partly in section;

Fig. 11 which is a plan of the positioning finger shown in elevation in Fig. 10;

Fig. 12 which is a side elevation of the same taken on the line 12—12 of Fig. 11;

Fig. 13 which is a side elevation of the stop motion control disks;

Fig. 14 which is a section of the same taken on the line 14—14 of Fig. 13;

2

Fig. 15 which is an elevation of one of the control disks;

Fig. 16 which is an enlarged, fragmentary elevation of a detail of a lever and its actuator;

Fig. 17 which is an enlarged, fragmentary elevation of a sub-assembly of the operating mechanism for raising the button clamp;

Fig. 18 which is a plan of the same; and

Fig. 19 which is a development of a cam.

10

General

The drawings disclose a machine for sewing buttons, having two or four holes, on to fabrics or other materials to which such buttons may be sewn. In general, such a machine includes stitch-forming mechanism for effecting the formation of stitches successively, some mechanism for effecting relative lateral movement of the button with respect to the stitch-forming mechanism, and mechanism for effecting a cyclic operation of the stitch-forming mechanism. These mechanisms are conjointly operated to effect a series of stitches with the thread passing in successive stitch-forming operations through different holes of the button and in consequence over the portion of the button between the holes. In this manner the button is sewn or bound to the fabric.

Commonly, the stitch-forming mechanism is the kind that operates upon a single thread. To this end, there is provided a needle bar for carrying the needle, and mechanism for reciprocating the needle bar. A looper cooperates with the needle. The looper is mounted below the bed of the machine and positioned and operated in timed relation with respect to the needle. On the downward or penetrating stroke, the needle passes through a hole in the button and through the fabric, carrying the thread with it. At the start of the return stroke, tension on the thread is released and a loop is cast because of the friction between the cloth and the thread. The looper catches the loop and a positioner arranges it such that on the next succeeding, penetrating stroke of the needle, the needle passes through the positioned loop cast on the last stroke of the needle. Thus, a series of stitches are formed.

Relative lateral movement of the button and needle to cause the needle to pass through different holes in the button on successive strokes may be effected by shifting or jogging the needle bar or by shifting the button. In the machine illustrated the button is shifted. To this end a shiftable button clamp is used and mechanism is provided for shifting the clamp in timed relation with respect to the needle. This mecha-

nism serves to vibrate the button clamp so that first one and then another of a pair of holes is aligned with the needle.

For a two hole button, vibration of the button clamp for a predetermined number of stitches is effected and then the machine is stopped. With a four hole button, the button clamp is positioned to present successively the holes of one pair, and after a predetermined number of stitches it is shifted to present the holes of the other pair of holes in the four hole button. At the end of the operation, tying stitches are effected to prevent the unraveling of the thread. For this purpose, the last several stitches are effected through the same hole in the button. If it be desired to eliminate what is termed a "cross over" stitch, that is a thread crossing over from one pair of holes to the other pair, in a four hole button, tying stitches are made before the button clamp is shifted and the thread is broken.

All of the foregoing mechanism is mounted in a single frame which, in the machine illustrated, includes a bed 1 supported on, and extending from, a base 2. A column or standard 3 extends vertically from the base. The column 3 supports a laterally extending arm 4 on the end of which there is a needle head 5. As the operator faces the free end of the arm 4, that is, the needle head 5, it is appropriate to designate this end of the machine as the front of the machine, and therefore, the column 3 is at the rear of the machine.

Stitch-forming mechanism

The stitch-forming mechanism includes a vertical needle bar 6 (Figs. 1, 2 and 3) that is slidably mounted in spaced bearings in the needle head 5. The needle bar is, in the usual manner, constructed at its lower end, to receive and retain a needle 7 having the eye at the point thereof. For the purpose of effecting stitches, the needle bar is reciprocated vertically to carry the end of the needle from a point above the bed of the machine to a point below the bed of the machine. To this end, there is (Fig. 2) a lever 8, mounted on a pivot 9 extending into and journaled in the arm 4 of the frame. One end of the lever receives a plunger 10 that is slidably mounted in the lever and that has a head 11 through which the needle bar extends and is pivotally secured. The other end of the lever is secured through a ball and socket connection to one end of a connecting rod 12 (Figs. 2 and 4), the other end of which is connected to the strap 13 (Figs. 4, 7 and 8) of an eccentric mounted on a main or power shaft 14.

The ball and socket connection (Figs. 2, 4 and 6) includes a pin 12a having a ball 12b on the end thereof. The pin extends through an opening provided therefore in the arm. Two such openings are provided, the one in which the pin is shown as being secured and another 12c spaced therefrom towards the pivotal axis of the lever. By shifting the pin 12a to the hole 12c a change in the stroke of the needle may be effected for different fabrics. In a machine constructed in accordance with this invention, a change in stroke may be made for example from a stroke of one and five-eighth inches for light work to a stroke of one and three-quarter inches for heavy work. The change from one length of stroke to the other is taken up upwardly such that the point of the needle moves to the same lowermost position irrespective of the length of the stroke.

The power shaft 14 (Fig. 7) extends transversely of the base of the machine, through both

sides, and is journaled in bearings provided theré-for at the sides of the base. A helical gear 15 mounted on the shaft 14 meshes with another helical gear 16 mounted on a looper shaft 17 extending forwardly of the machine and journaled in bearing brackets 18 and 19 extending from the bed of the machine adjacent the forward and rear ends respectively. Through this connection, the looper shaft is continuously rotated, in the direction of the arrow (Figs. 2 and 7) as the needle bar is reciprocated. The end of the looper shaft extending forwardly through the bearing bracket 18 is reduced in diameter and is received in a fixture 20 which is secured to the looper shaft by set screws. In an axial opening in the opposite end of the cam fixture, a stub shaft of a hook-shaped looper 21 is received and secured therein, for rotation therewith, by set screws.

As the thread loops are thrown at the start of the return stroke of the needle the rotating looper takes the loop, twists it through one hundred and eighty degrees and holds it until the next succeeding penetration of the needle after which by virtue of the position to which the hook-shaped looper has rotated, the loop is cast off the looper. To position the loop held by the looper, there is a positioning finger 22 (Figs. 10, 11 and 12) arranged to cooperate with the looper. This positioning finger is mounted on a yoke 23 that embraces a three point cam 24 on the cam fixture 20. The yoke has oppositely extending lateral arms 25 that are received in and slidably in grooves provided therefor in and transversely of the bed. The positioning finger is formed on a plate 26 that is received in a groove in the top of the yoke extending parallel to the looper shaft. The plate is held in a slot in the yoke by a dowel pin. The positioning finger lies directly below a needle plate 27 which, when removed, provides access to the positioning finger, supporting yoke and cam fixture. It will be seen (Fig. 10) that when the looper shaft is rotated the yoke and in consequence the positioning finger are reciprocated transversely of the path of the needle. In this way the positioning finger takes the loop held by the looper and positions it to position the loop for proper correlation with the point of the looper and to receive the needle on the penetrating stroke of the needle.

Associated with the positioning finger plate there is an adjustable needle guide. This consists of a strip 28 having a downward extension 28a shaped as shown (Figs. 11 and 12). The strip 28 is received in a longitudinally extending slot in the forward end of the bed and has a slot 28b therethrough through which a machine screw 28c extends to secure the guide to the bed. The positioning finger plate 26 has a downward extension 26a which forms a needle guide slot with the needle guide. The needle guide like the positioning finger are below the needle plate 27.

For holding a button in position during the stitching operation there is provided a button clamp (Figs. 1, 2, 3 and 8). This button clamp is secured to a bracket 29 at the forward end of the bracket. The rear end of the bracket 29 has spaced depending lugs 30 that are pivotally secured by means of a pivot pin 30a to the lugs 31 extending from a lever 32. This lever 32 is for vibrating and shifting the button clamp and for this reason, it is pivotally secured to the bed of the machine by a pivot screw 33. The head 75 34 (Fig. 9) of the pivot screw engages the under

side of the bed 1 of the machine and the pivot screw extends through an elongated slot 35 through the bed of the machine. The lever 32 is provided with a like elongated slot 36 of greater width than the width of the slot 35. A bushing 37 is received in the slot 36 and engages the upper surface of the bed 1. In this bushing a cylindrical extension on a nut 38 is received, the nut being threaded on to the pivot screw. Between the nut and the lever, there is an indicator bracket 39 having an indicator point 40. The bracket is provided with oppositely depending ears 39a that extend into the slot 36 and prevent the indicator bracket from turning on the pivot. The indicator point extends over an indicator plate 41 secured to the bed and extending parallel to the slots. This indicates the throw, or extent of vibration or, the clamp for various positions of the pivot along the slots.

The lever 32 is vibrated about the pivot screw 33 to cause a button held by the button clamp to present successively the holes of a two hole button or the pair of holes of a four hole button to the needle as the needle is reciprocated. For this purpose, the lever includes an arm 42 (Figs. 2 and 8) that extends rearwardly of the lugs 31, into the column 3 just above the base and over the top plate 43 of the base. To the end of the arm 42, of the lever 32, there is pivotally secured one end of a link 44, and the other end of which is pivotally secured to one end of a lever 45. The other end of the lever 45 is pivotally secured to the plate 43 by a pivot screw 45a. Intermediate the ends of the lever 45 and adjacent the end to which the link 44 is connected, a cam follower pin 46 is threaded into the link 44. This pin extends through the link 44, a slot provided therefor in the plate 43 and into the track of a positive, sinuous cam 47. The track (Fig. 19) of the cam 47 is formed in the edge of the cam and the cam is mounted on a horizontal cam shaft 48, journaled in bearing lugs formed on the inner surfaces of the sides of the base.

The cam shaft 48 (Figs. 7 and 8) to which the cam 47 is secured for rotation therewith is driven from the looper shaft 17. The drive is through two helical gears, one 49 secured on to the looper shaft 17 and the other 50 secured on the cam shaft 48. Thus, it will be observed that as the cam 47 is rotated the lever 45 is vibrated about its pivot 46 and through the link 44 vibrates the lever 32 about the axis of the pivot screw 33. As the pivot screw 33 constitutes the fulcrum of the lever 32, a shifting of the pivot screw along the slots 35 and 36 will vary the throw of the button clamp.

In order to accommodate a four hole button in a machine in which the needle moves in a fixed path, it is necessary to be able to shift the button clamp supporting lever longitudinally, that is in a forward and rearward direction. In this way first one pair of the holes of a four hole button may be successively presented to the needle and then the other pair of holes. In the machine illustrated this longitudinal movement of the button clamp supporting lever 32 is accomplished by the following mechanism (Figs. 2 and 8): One end of a control lever 51 is pivotally secured to the arm 42 of the lever 32 through a link 51a. This control lever has a resilient extension 52 extending through the column and out at the rear of the column, providing at the rear of the machine a finger piece by which the lever may be adjusted. Extending from the side

edge of the lever 51, there is a lug 53, through which a pivot pin 54 extends. This pivot pin is secured to a yoke 54a which embraces an elevated, arcuate central rib 55 extending from a lever bracket 56 of the bell crank type. The lever 56 is pivoted to the plate 43 through a countersunk pivot screw 57. An arm 58 of the lever carries, adjacent the end thereof, a cam follower pin 59 which is secured therein and extends into the track of a positive track cam 60 mounted on the cam shaft 48. The cam 60 has a track in the edge thereof, one half of which is offset axially with respect to the other half. Between the lug 53 and the end of the lever 51 that is pivoted to the lever 32, one end of a link 61 is pivotally connected to the lever. The other end of the link 61 is pivotally secured to the plate 43 in line with the pivotal axis of the lever bracket 56.

From the foregoing it will be apparent that as the cam 60 rotates, and the cam follower pin 59 meets an offset in the cam track, the bracket lever 56 will be moved about its pivotal axis. In the position illustrated in Fig. 8, the lever 51 will be moved longitudinally, and by virtue of the link 61, the lever 32 will be moved longitudinally in a straight line movement. The amount of movement of lever 32 will depend upon the distance between the pivot screw 57 and the pivot pin 54. If the lever 51 is shifted such that the pivot pin 54 is directly over the pivot screw 57, there will not be any longitudinal movement of the levers 51 or 32 when the lever bracket is moved. This is the position of the lever 51 for sewing a two hole button. For a four hole button the lever 51 is shifted away from this position an amount depending upon the size of the button or rather the distance between the button holes.

The extent of the longitudinal shifting of the lever 32 is proportional to the distance the pivot pin 54 is from the pivot 57. On the rear of the standard 3, there is secured a marked indicator 52a having marked thereon distances of movement of the lever 32 for various positions of the extension 52. The extension 52 is provided with an arrow 52b for this purpose. Detents on the indicator 52a and the extension 52 may serve to hold the extension 52 in any set position.

As the clamp vibrating cam 47 and the clamp shifting cam 60 are secured on the same shaft, the same number of stitches, for a given operation of the machine (one revolution of the cam shaft) will be made whether a two or four hole button is being sewn, except for the modification of the mechanism as hereinafter described. In the case of a four hole button one half of the number of stitches will be made in each pair of holes. The track of the cam 47 is developed in Fig. 19, from which it will be seen that at spaced intervals, such as at 47a, 47b, there is a straight portion. As the cam follower pin 46 rides in these portions of the cam two or more stitches are made in the same hole to effect tying stitches. For a four hole button such tying stitches are made just before the lever is shifted and at the end of the sewing operation.

Stop motion

After making a predetermined number of stitches, the machine is stopped. As in the machine illustrated, the stop-motion mechanism may be set to stop the machine after a one-half revolution of the cam shaft 48 when two hole buttons are being sewn, or after a full revolution of the cam shaft when four hole buttons are being

sewn. In this way twice the number of stitches are used for a four hole button, each pair of holes receiving the same number of stitches as a two hole button.

Machines of this kind operate at comparatively high speed and the momentum of the mechanism must be absorbed quickly and the machine stopped with the needle withdrawn in its uppermost position. This is accomplished in the machine illustrated by absorbing the momentum by springs which also serve to center the driving shaft and so stop the machine in the desired position of the mechanism. The main drive shaft 14 (Figs. 4 and 5) is driven through a pulley 62 that is free on the end of the shaft. On its outer side the pulley engages, through a thrust bearing, a spherical-sector head 63 which is engaged by the wedge-shaped end of a lever 64. On its inner side, the pulley is provided with a frustro-conical surface 65 which is positioned to cooperate with a complementary frustro-conical surface 66 of a disk 67. The disk 67 is also free on the shaft 12, but the diameter of the shaft receiving hole through the disk is somewhat greater than the diameter of the shaft so that the disk is free to "float," that is, move a limited amount in all lateral directions. Adjacent the disk 67 and secured on the shaft for rotation therewith, there is a heavier or thicker disk 68, having a hub 69 between which and the shaft bearing there is a thrust bearing 70. The disk 68 is secured to the disk 67 for rotation therewith by screws 71 threaded into the disk 68 and having elongated heads extending through openings in the disk 67. The openings in the disk 67 for the heads of the screws 71 are larger in diameter than the heads of the screws so that they do not interfere with the float of the disk 67. The pulley which is slideable on the shaft 12 is normally spring pressed by a spring 72 away from, and out of driving relation with, the disk 67.

The disk 68 (Figs. 2, 4 and 5) forms a part of the stop-motion mechanism. It cooperates with a resiliently centered plunger 73 having a lug 74 extending therefrom. Within a circumferentially extending slot 75 in the disk 68, there is pivotally mounted a latch 76 on a pivot pin 77. The latch 75 is spring pressed by a spring 78 to a position in which it extends beyond the peripheral edge 79 of the disk 68. The latch 76 is provided with a transverse slot or notch 80 which is of sufficient width to receive the lug 74 on the plunger 73.

The resiliently centered plunger is slidably mounted in and extends through a pivotally mounted housing 84. The housing is divided at the longitudinal center by a partition 85 which constitutes a bearing for the plunger and an abutment for springs 86 and 87. The spring 86 acts between the partition 85 and a shoulder formed by an enlargement 88 on the plunger. The spring 87 acts between the partition 85 and a nut 89 threaded on to the end of the plunger. The housing 84 has a bracket 90 formed thereon which is secured to a shaft 91 extending between and through the side walls of the base in which it is journaled. An arm 92 extends from the bracket 90 and a spring 93 engaging the arm 92 and a pin 94 in the side of the base acts to resiliently urge the housing in a direction to cause the lug 74 to engage in the notch 80 in the latch 76. The housing 84 may be moved to release the lug 74 from the notch 80 through a foot treadle (not shown) connected to an extension 95 at the rear of the housing.

When the lug 74 is raised out of the notch 75

75, the lever 64, which is secured on to the end of the shaft 91, is raised. The wedge-shaped end 98 of the lever acting on the spherical sector head presses the head inwardly. The head 63 is formed on a plunger slidably mounted in the end of the shaft 14 and upon being moved inwardly forces the pulley into driving relation with the floating, frustro-conical disk 67. The pulley is continuously driven by an electric motor (not shown) so that when the lug 74 is out of the notch 80, the shaft 14 starts to rotate in the direction of the arrow (Figs. 2 and 3). When the foot treadle is released, the lug 74 rides on the edge of the disk 68.

15 With this arrangement, without the control hereinafter described, the machine would continue to operate for one revolution of the drive shaft 14. As the lug 74 approached the latch 76, it would depress the latch, permitting the housing, under the action of the spring 93 to move about its pivot. This action serves to release the cone clutch, and when the lug 74 abuts against the edge of the notch 80 the clutch is completely released. The latch returns to its normal position when this occurs and the lug is held in the notch. The resiliently centered plunger absorbs the momentum and the rebound without undue shock to the mechanism.

20 As the cam shaft 48 is geared to the drive shaft in a relation such that the drive shaft makes sixteen revolutions for each revolution of the cam shaft, controls are provided so that the stop-motion mechanism, above described, may actuate either after eight or sixteen revolutions of the main shaft, eight revolutions being sufficient for a two hole button and sixteen being required for a four hole button. In the machine illustrated this control acts upon the shaft 91.

25 On the opposite end of the shaft 91 (Figs. 3, 8 and 13) there is secured a lever 99 which carries a cam follower 100. The cam follower 100 is positioned to engage the edges of control disks 101 and 102 mounted on the cam shaft 48. The disk 101 is provided with a hub 103 through which it is secured to the cam shaft 48 for rotation therewith. The disk 102 is loosely mounted on the shaft but it is secured, through an adjustable connection, to the disk 101. The diameter of the disks are equal and such in relation to the position of the disks lever 99 that when the cam follower 100 rides on the edge of the disks, the shaft 91 is positioned to hold the lug 74 out of the notch 80 in the latch 76. The disk 101 has two radial notches 104 and 105 at diametrically opposite points, each of which is wide enough to receive the cam follower 100. The disk 102 likewise has two radial notches 106 and 107 at diametrically opposite points of the same depth as the notches 104 and 105. The notch 106 is, however, elongated.

30 An arcuate slot 108 is provided, in the disk 101 and at each end of the slot, there is a recess, of a larger diameter than the width of the slot, in the outer surface of the disk, such as the recess 109. The end of a fitting 110 is received in the recesses at the ends of the slot. The fitting is hollow and receives the head of a screw 111. This screw extends through the fitting, the slot 108 and into a threaded opening 112 in the disk 102. A spring 113 within the fitting abuts against the head of a screw 111 and the base of the fitting, acting to draw the disks together and hold the fitting in a recess. By withdrawing the fitting against the action of the spring and moving it 35 to the recess at the opposite end of the slot, the

position of the disk 102 may be changed with respect to the disk 101.

As seen in Figs. 13 and 15, the disks are so related that there are two diametrically aligned notches into which the cam follower 100 may enter. This is the relative position of the disks for sewing two-hole buttons, that is, wherein the drive shaft makes but eight revolutions and the cam shaft one-half revolution when the stop motion operates to stop the machine. By shifting the fitting 110 to the recess 109, the disk 102 will be moved counter clockwise (Figs. 13 and 15) and the notch 101 will be closed. Because of the elongated notch 106 in the disk 102, however, the notch 104 will remain open to receive the cam follower, and in consequence, when the cam shaft makes one half revolution, the plunger housing will be held suspended and the lug 74 will not drop into the notch 75 in the disk 78. On the next half revolution of the cam shaft, the cam follower will drop into the notch 104 and the stop mechanism will operate to stop the machine.

Thread handling mechanism

Concomitantly with the operation of the machine, in proper sequence and in timed relation with the stitch-forming and tying operations, the thread is subjected to various tensions and strains and nipped or broken. The mechanism for performing the functions is here termed the thread handling mechanism. At the rear of the column 3 of the machine, a bracket 114 is secured for holding a spool of thread which, of course, is free to rotate as the thread is withdrawn. From the spool the thread is lead through certain tension devices and eventually through the eye of the needle.

On the top of the arm 4 (Figs. 2 and 6) of the frame, there are three posts 115, 116 and 117 extending vertically from the arm along the centerline thereof, and a fourth post 118, spaced longitudinally of the arm. Forwardly of the post 118, there is a square block 119 secured on the arm and extending therefrom. Between the posts 115 and 116, there is a thread tension device 120, of the usual and well known kind, consisting of a pair of tension disks 121 and 122 resiliently urged together by a spring 123. Between the posts 116 and 117 and over the shaft 9, there is another thread tension device 124.

The tension device 124 includes a pin 125 which extends into the arm of the machine in cooperative relation with respect to a cam surface 126 on the shaft 9. With the movement of the shaft 9, the pin is elevated concomitantly with the stitching operation to release the tension on the thread. The tension is released on each stitching operation to permit the looper to draw off the necessary thread for twisting and positioning the loop.

Also mounted on the arm 4 of the frame, there is a thread pull off device. This consists of a bell crank lever 127 pivotally mounted on a pivot screw 128. The lever includes a pair of arms 129 and 130 the ends of which are spaced apart and each of which has an upstanding finger, the fingers 131 and 132 respectively. At the end of each stitching operation, in a manner herein-after described, the lever 127 is actuated to cause the fingers 131 and 132 to draw off sufficient thread for the start of the next stitching cycle.

Cooperating with the block 119 (Fig. 6), there is a flat extension 133 formed as a part of a bell crank lever 134. The lever 134 is mounted on a pivot pin 135 secured in the arm 4. At the end of a stitching cycle, as and in the manner here-

in after described, the bell crank lever 134 is actuated to nip or squeeze the thread between the extension 133 and the adjacent flat surface of the block 119. The lever 134 also carries a horizontal post 135 under which the thread passes in passing to an opening through the upper end of the needle bar.

The front of the needle bar head (Figs. 1 and 10), is covered by a plate 136. On this plate there is a leaf-spring thread tension 137 held in place by a machine screw 138. Through a slot in the plate a bar 139 extends, and secured in the bar, there is a rod 140 having an outwardly turned end. Additional rods 141 and 142 are secured to the plate and each has an arm extending transversely of the plate and spaced therefrom. The rod 140 is between the rods 141 and 142. These rods serve to place, at the end of a stitch cycle, a preliminary strain on the thread to more readily effect a breaking of the thread at the end of the tying stitches.

The foregoing operative parts, those actuated at the end of a stitch cycle, are actuated through the rod 139. The rod 139 extends along the side 25 of the arm 4 and it is slidably mounted therein. It is normally resiliently urged to its rearmost position by a spring 143. The end of the bar has a transverse extension 144 which is in cooperating position with respect to one end of a bell 30 crank lever 145, pivoted on a pivot screw 146. On the bar 139, intermediate the ends thereof there is a fitting 147 having an extension 148 (Fig. 6) which on forward movement of the bar engages between the disks of the tension device 121 and 35 relieves the tension on the thread. The lever 127 is actuated by the bar 139 through a stud 149 extending from the lever and engaging in a yoke 149a on the bar. A like stud 150 extending from the lever 134 is positioned to be engaged by a 40 block 150a on the bar 139 to actuate the lever 134. The lever 134 is spring urged by a spring 134a to a position in which the surface 133 engages the block 119. When the bar 139 is in the 45 rearmost position the block 150a holds the lever against the action of the spring.

At the end of a stitch cycle, the bar 139 is moved forwardly. This action is effected through a lever (Fig. 3) 151 rotatably mounted on the extended end of the shaft 9 and having an arm 152 in cooperative relation with respect to a stud 153 extending from the bar 139. The other arm of the lever 151 is connected through an adjustable pivot screw 154 adjustable in a slot 155 in the arm of the lever 151, to one end of a link 156. At the other end of the link 156 there are two 55 spaced notches 157 formed in the link, either of which may receive a pin 158 extending from a lever 159 adjacent the end thereof. The lever 159 is rotatably mounted on the drive shaft 14 and has a curved end section 160 that is positioned to be engaged (Fig. 16) by a cam 161 secured on the cam shaft 48.

The cam 161 is in effect a two point cam having two lever-engaging points 165 and 166 at diametrically opposite points. As the cam 161 is mounted on the cam shaft, the bar 139 is actuated for each half revolution of the cam shaft—twice for each revolution of the cam shaft. Thus, as the drive shaft makes eight revolutions for a cycle of stitches for two holes in a button, the bar 139 is actuated after each such cycle.

The thread (Figs. 1 and 6) indicated by the line 167 passes from the spool at the rear of the machine, along one side of the post 115, through the tension device 120, across the post 116,

through the tension 124, and past the post 117. It will be noted that the thread passes on opposite sides of the successive posts and tension devices. Thus, the posts serve to maintain the thread in the tension devices. From the post 117 it passes along the post 118, on the same side thereof as the post 117. It is lead from the post 118 between the block 119 and the extension 133 of the lever 134. Next it passes under the horizontal post 135 on the lever 134. From the post 135, the thread passes (Figs. 1 and 10) through an opening provided therefor adjacent the top of the needle bar. Then (Fig. 10) the thread passes down the cover plate of the needle bar, under a rod 162 and the rod 142, over the rod 140 and under the stationary bar 141 and under the leaf-spring 137. The thread is then passed through a thread hole in the plate and the eye of the needle. Between the rods 162 and 142, the thread passes through the loop of a spring 163 secured to the plate and extending under the rod 140.

During the stitching cycle, the stitches, as heretofore described, are formed the tension device 124 being released in the manner stated during each reciprocation of the needle. At the end of the stitching cycle, the bar 139 is actuated to release the automatic tension 121, actuate the lever 127, release the lever 134, and move the bar 140 outwardly which places a preliminary strain on the thread. This is effected through movement of the lever 159.

While the bar 139 is at its rearmost position, the spring 137 is held away from the plate 136 and does not place any tension on the thread. This is effected through a lever 137a (Fig. 3) pivoted on a lug 137b secured to the plate. One arm of the lever has an extension 137c extending through a slot in the plate and engaging the spring 137. A spring 137d acts between the other leg of the lever and the rear of the plate 136 and during stitching operations holds the spring 137 away from the plate in opposition to the adjustable spring 137e tending to press the leaf spring 137 against the plate. When the bar 139 moves forward at the end of a stitch cycle, a pin 137f thereon engages the lever 137a and releases the leaf spring 137. The leaf spring 137 then clamps the thread to the face of the plate 136.

Upon movement of the bar 139, forwardly, the lever 134 is moved so that the thread is clamped between the block 119 and the extension 133 of the lever 134. The stitch forming mechanism has, at this time, completed a tying stitch. Upon movement of the bar forwardly the U-shaped bracket 140 is, of course, moved forwardly and as the thread is held between the tying stitch and the clamp extension 133, it is strained. The automatic tension 121 is released so that on the actuation of the lever 127, a quantity of thread is pulled off, an amount sufficient to start the next stitching operation. This action takes place as the needle starts its return stroke. Further movement of the needle, causes the thread to break at the tying stitch and it is not therefore withdrawn from the needle.

At the end of a stitch cycle, the button clamp is lifted. The button clamp, hereinafter described in detail, is, as previously described, secured to the bracket 29 which is pivoted to the lever 32. Secured to the lever 32, there is also a feed plate 168 which extends forwardly of the lever 32. The feed plate has an opening therethrough for the needle, the opening being of a size sufficient to permit the passage of the needle irrespective of the position of the plate. It is also

provided with a knurled surface. On this feed plate the cloth is placed and the button clamp is moved down, holding a button, so that the button clamps the cloth to the feed plate. To this end the bracket 29 is urged about its pivotal connection to the lever 32 by a spring pressed plunger 169. The plunger 169 is slidably mounted on a stud 170 extending from the arm 4 abuts against the bracket 29. A spring 171 acts between an adjustable finger nut 172 on the plunger and the arm 4 of the machine.

For raising the bracket 29 and in consequence the button clamp, the bracket 29 is provided with a boss 174 in which one end of a rod having a horizontal arm 175 is secured. Extending below the arm 175 is the arm 176 of a rod 177 that is secured in one end of a lever 178. The lever 178 is pivotally mounted on the extending end of the shaft 9 and when actuated in one direction serves to elevate the bracket 29.

The lever 178 is actuated through a bar 179 which is pivotally secured, at one end, to the lever and which extends down through the column of the machine to the base. The lower end of the bar 179 is pivotally secured to one end of a link 180 (Figs. 4, 17 and 18), the other end of which link is pivotally secured to the end of a bracket or lever 181 secured to the shaft 91 for movement therewith. Adjacent the lower end thereof, the bar is provided with a notch 182 in the edge thereof forming a shoulder 183.

The bar 179 is depressed at the end of a stitch cycle by a cam follower bracket 184. The bracket 184 is pivoted on a shaft 185 and has a U-shaped section embracing an eccentric cam 186 mounted on the shaft 14. Cam engaging surfaces 187 and 188 engage the cam 186 and the bracket is oscillated as the shaft 14 rotates. An arm 189 on the bracket has a lateral extension 190 which under certain conditions engages the shoulder 183 and actuates the bar 179 to lift the button clamp.

When the plunger housing 84 is raised in starting the machine in the manner previously described, the shaft 91 is actuated. It is turned clockwise, as seen in Fig. 17. The bracket 181, through the link 180 moves the bar 179 such that the extension 190 on the cam follower bracket 184 is out of the notch 182. It is held in this position, as previously described through the stitch cycle, at the end of which the cam follower 100 drops into a notch in the cycling cam disks 101 and 102 and the lug 74 on the plunger 73 drops into the notch 75. At this time, the shaft 91 moves counter clockwise (Fig. 17) and on the succeeding oscillation of the bracket 184 the extension 190 engages the shoulder 183 and so effects a lifting of the cam bracket 29.

With the lifting action of the clamp, and through the mechanism just described, there is provided an additional arrangement for effecting movement of the bar 139. This is effected through the bell crank lever 145 one end of which is in cooperating relation with respect to the end extension 144 of the bar 139. The other end of the lever extends under a pivot pin 191 securing the bar 179 to the lever 178. Thus, when the bar 179 is moved downwardly, the bar 139 is moved forwardly through the action of the lever.

The button clamp may be any one of many well known in the art. The particular button clamp illustrated is comparable to that disclosed in United States Patent No. 2,009,560 issued July 30, 1935 with one exception. In the button clamp illustrated, the position of the adjusting pin 192 (Fig. 8) is positioned and held

in place by a lever 193. The lever is pivoted at one end on a pivot screw 194 and traverses the path of the adjusting pin 192. Adjacent its opposite end, there is an arcuate slot 195 through the lever and through which a clamping thumb screw 196 extends. An upturned flange 197 formed adjacent the end of the lever constitutes a finger piece for moving the lever. By loosening the thumb screw and moving the lever, the adjusting pin may be set at any position. This determines the amount the jaws 198 will close.

The machine also includes what may be termed a thread wiper for moving and holding the free end of the thread to the rear of the needle so that it does not interfere with inserting a button between the jaws of the button clamp. This thread wiper (Figs. 1 and 3) consists of a stiff wire 199 secured to and extending from one arm of a lever 200. The wire 199 has an end section 201 that extends substantially horizontally and the wire is of sufficient length so that in the upper position of the needle, the end section 201 can swing under the needle. The lever 200 is pivoted to the frame at 202 and includes an arm 203 upon which a spring 204 acts to move the lever such that the wire is positioned to the rear of the needle. Another arm 205 of the lever is in the form of a yoke, one arm 206 of which is longer than the other. A bracket 207 is secured on the bar 139 and carries a pin 208 which engages in the yoke of the lever 200.

In the position illustrated in Fig. 3, the inoperative position of the machine, the bar 139 is in its most forward position. The wiper is in its rearward position. When the machine is started, the bar 139 is released and immediately moves to its rearmost position. In doing so, the pin 208 moves the lever 200 to bring the wiper to a position in front of the needle. The arm 206 of the yoke on the lever lies, in the inoperative position of the parts, in the path of a block 209 secured on the needle bar 6. It is, however, upon rearward movement of the bar 139, moved out of the path of the block 209. This is to prevent downward movement of the needle before the wiper has been moved to a position forwardly of the needle.

At the end of a stitching cycle, the machine is stopped and the thread broken as heretofore explained. The bar 139, upon the stopping of the machine is moved to its forward position. In doing so the spring 137d is released and the wiper is moved to its rearmost position. The spring 137d takes up part of the slack in the thread insuring that the free end is withdrawn and the wiper moves the free end rearwardly of the needle as illustrated in Fig. 3.

Operation

In operating the machine, the operator places a button between the jaws of the button clamp. This is done simply by pressing the edge of the button between the jaws 198 until it engages a stop 210. The jaws yield to receive the button and hold it when it is inserted between them. The clamp has, of course, been previously adjusted for the particular size button to be sewn. Also the finger lever 52 has been adjusted for the particular button, that is, for a two or four hole button as the case may be, and if for a four hole button for the distance between the two pair of holes. Likewise, the control disks 101 and 102 have been adjusted for the particular

button, i. e., a two or four hole button. In addition, the pivot screw 33 has been adjusted in accordance with the distance between the holes of a pair of holes in the particular button to be sewn.

After the button is placed between the jaws of the clamp, the fabric to which the button is to be sewn is placed on the cloth plate 168. The operator then presses the foot treadle (not shown) which elevates the plunger housing 84 and removes the lug 78 from the notch 80. Simultaneously, the lever 64 is elevated and the wedge-shaped end thereof causes the cone clutch to engage, connecting the drive shaft 14 to the pulley 62. Also, the shaft 91 is rotated and the cam follower 100 moved out of the notch in the control disks. When the operator releases the foot treadle, the cam follower 100 rides on the edge of the control disk and maintains the plunger housing 84 and the lever 64, elevated.

Immediately upon movement of the shaft 91, the link 179 (Figs. 17 and 3) is released. The lever 178 is, thus, released and the button clamp moves down to clamp the fabric between the button and the cloth plate. The bar 139 is also released and moves to its rearmost position. When this occurs, the automatic tension becomes operative, the lever 121 is moved to release the thread it took off when the machine stopped, the nipper lever 134 is actuated to release the thread, the spring 137d is retracted, the bar 140 is withdrawn, the tension 137 is released, and the wiper 199 moves to its position forwardly of the needle. The machine operates to effect stitches successively through different holes of a pair of holes in the button and at the end of a stitch cycle to effect tying stitches.

If a four hole button is being sewn, then after the tying stitches for the first pair of holes, the lever 159 is actuated to move the bar 139 forward. With this action the thread handling mechanism comes into play to break the thread. The lever 32 is moved rearwardly to bring the second pair of holes of the button into position. This is done without interruption of the operation of the stitch-forming mechanism.

At the end of a stitch cycle, the cam follower 100 drops into a notch in the control cams. This releases the shaft 91 so that the stop-motion mechanism becomes effective. Also the link 179 is positioned to be engaged by the extension 198 of the bracket 184. The button clamp is thus raised and the bar 139 is moved forward. The thread handling mechanism comes into play and the thread is broken. The button is removed from the button clamp and the machine is ready to repeat the operation.

It will be obvious that various changes may be made by those skilled in the art in the embodiment of the invention illustrated in the drawings and described in detail above within the principle and scope of the invention as expressed in the appended claims.

I claim:

1. In a sewing machine having stitch-forming mechanism and operating mechanism therefor, thread handling mechanism comprising in combination a releasable thread tension device, means for releasing the tension device, thread clamping means between said tension device and the stitch-forming mechanism, means for drawing off thread positioned between said tension device and said thread clamping means, and means operative upon the formation of a predetermined number of stitches for actuating said tension device re-

leasing means, said thread clamping means, and said means for drawing off thread.

2. In a sewing machine having stitch-forming mechanism including a needle and means for reciprocating the needle, thread handling mechanism comprising in combination, a releasable thread tension device, means for releasing the thread tension device, thread-clamping means between the tension device and the needle, means for drawing off thread positioned between the tension device and the thread-clamping means, and common actuating means therefor automatically operable to simultaneously actuate said means for releasing the thread tension device and said clamping means.

3. In a sewing machine having stitch-forming mechanism including a needle, and means for reciprocating the needle, thread-handling mechanism comprising in combination a releasable tension device, means for releasing the tension device, thread-clamping means between the tension device and the needle, means for drawing off thread positioned between the tension device and the thread clamping means, thread tensioning means positioned between the thread clamping means and the needle operative to effect an elongation of the thread between the clamping means and the needle, and means operative upon the formation of a predetermined number of stitches for effecting the operation of the thread handling mechanism.

4. In a sewing machine having stitch-forming mechanism, operating mechanism therefor and thread control means operative upon the thread passing to the stitch forming mechanism; the combination for actuating the thread-control means, comprising an oscillating lever, an operating element, and means for effecting a connection between said oscillating lever and said operating element upon the formation of a predetermined number of stitches.

5. In a sewing machine having stitch-forming mechanism and operating mechanism for the stitch-forming mechanism, the combination comprising a needle bar head, a face plate on said needle bar head, a leaf-spring thread tension device on said face plate, positioned to cooperate with the face plate to place tension on a thread therebetween, means for releasing said thread tension, and means actuated by said operating mechanism for rendering said releasing means ineffective.

6. In a sewing machine having stitch-forming mechanism, the combination comprising a thread tension, means for releasing said tension, a thread-clamp located intermediate the thread tension and the stitch-forming mechanism, thread tensioning means located intermediate the thread clamp and the stitch-forming mechanism, means for operating the machine through a predetermined sewing cycle, means for actuating said first mentioned thread tension and thread clamp and severing the thread a plurality of times during said sewing cycle.

7. In a sewing machine having stitch-forming mechanism, a thread tension, means for reeling said tension, thread pull-off means located intermediate the thread tension and the stitch-forming mechanism, a thread clamp located intermediate the thread pull-off means and the stitch-forming mechanism, thread tensioning means located intermediate the thread clamp and the stitch-forming mechanism, means for operating the machine through a predetermined sewing cycle, and means for actuating said first men-

tioned thread tension, thread pull-off means, and thread clamp a plurality of times during said sewing cycle.

8. In a sewing machine having stitch-forming mechanism, a thread tension, means for releasing the thread tension, thread pull-off means located intermediate the thread tension and the stitch-forming mechanism, a thread clamp located intermediate the thread pull-off means and the stitch-forming mechanism, thread tensioning means located between the thread clamp and the stitch-forming mechanism, thread-end moving means located intermediate the thread tensioning means and the stitch-forming mechanism, means for operating the machine through a predetermined sewing cycle, and means for actuating said first mentioned thread tension, thread pull-off means, thread clamp and thread-end moving means a plurality of times during a sewing cycle.

9. In a sewing machine having stitch-forming mechanism, a thread tension, means for releasing the thread tension, thread pull-off means located intermediate the thread tension and the stitch-forming mechanism, a thread clamp located intermediate the thread pull-off means, and the stitch-forming mechanism, thread tensioning means located between the thread clamp and the stitch-forming mechanism, thread-end moving means located intermediate the thread tensioning means and the stitch-forming mechanism, means for operating the machine through a predetermined sewing cycle, and means for actuating said first mentioned thread tension, thread pull-off means, thread clamp and thread-end moving means a plurality of times during said sewing cycle including a slidably mounted bar, means on the bar for effecting the actuation of said instrumentalities, and means for actuating the bar a plurality of times during said sewing cycle.

10. In a sewing machine having stitch-forming mechanism, a thread tension, means for releasing the thread tension, thread pull-off means located intermediate the thread tension and the stitch-forming mechanism, a thread clamp located intermediate the thread pull-off means and the stitch-forming mechanism, thread tensioning means located between the thread clamp and the stitch-forming mechanism, thread-end moving means located intermediate the thread tensioning means and the stitch-forming mechanism, means for operating the machine through a predetermined sewing cycle, and means for actuating said first mentioned thread tension, thread pull-off means, thread clamp and thread-end moving means a plurality of times during said sewing cycle including a slidably mounted bar, means on the bar for effecting the actuation of said instrumentalities, and means for actuating the bar at the end of a sewing cycle.

GEORGE WILLIAM NELSON.
